UNITED STATES PATENT OFFICE.

JEAN G. C. COTTIER, OF NEW YORK, N. Y.

DESIGN FOR A PRECIOUS OR IMITATION STONE.

SPECIFICATION forming part of Design No. 20,043, dated July 22, 1890.

Application filed April 18, 1890. Serial No. 348,656. Term of patent 7 years.

To all whom it may concern:

Be it known that I, JEAN G. C. COTTIER, a citizen of the United States, residing at New York city, in the county and State of New York; have invented and produced a new and original Design for Precious or Imitation Stones, of which the following is a specification, reference being had to the accompanying drawings, forming a part thereof.

Figure 1 represents a plan view of a stone shaped in accordance with my design, and Fig. 2 is a side elevation of the same.

The leading feature of the design consists in a face of triangular contour, as at A, and

15 a correspondingly-shaped table, as illustrated

at B in Fig. 1. The facets C of the face approximate triangular figures. The collet is likewise triangular, and the facets thereon approximate a similar shape, as illustrated at D in Fig. 2.

I claim—

In a design for precious or imitation stones, a triangular face, and a table of corresponding contour, substantially as shown and described.

JEAN G. C. COTTIER.
